UNITED STATES PATENT OFFICE.

JOHN J. DOLAN, OF CAMPELLO, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TOE-REST FOR LASTING-MACHINES.

1,295,135.

Specification of Letters Patent. Patented Feb. 25, 1919.

Application filed July 30, 1915. Serial No. 42,736.

To all whom it may concern:

Be it known that I, JOHN J. DOLAN, a citizen of the United States, residing at Campello, in the county of Plymouth and State of Massachusetts, have invented certain Improvements in Toe-Rests for Lasting-Machines, of which the following description, in connection with the accompanying drawings, is a specification, like reference characters on the drawings indicating like parts in the several figures.

This invention relates to lasting machines and particularly to a toe rest for use upon lasting machines of the bed type.

It is very desirable during the lasting operation upon a shoe toe to apply sufficient pressure along the tip seam to prevent displacement of any portion of the tip seam toward the toe by the lasting instrumentalities. It has been the experience under commercial conditions that frequently too much pressure is applied locally to the mid portion of the tip seam, the effect of such pressure appearing as a blemish upon the lasted upper.

Features of the invention consist in a novel organization comprising instrumentalities tending to displace the tip seam, a hold-down for applying pressure to the shoe, and a toe rest having a resilient member with a portion thereof removed below the part of its surface on which the shoe rests so that it will yield to pressure of the shoe and engage the shoe over a more extended area to distribute the pressure on the tip seam. As shown herein the rest member is a block of resilient material, for example, rubber, having an approximately flat toe engaging surface and centrally beneath this surface is formed a recess extending from front to back. This recess or cavity diminishes the resistance of the pad at this point and enables the lateral portions of the pad to come into firmer engagement with the shoe than they would otherwise do.

Another feature of the invention consists in interchangeable means located in the recess or cavity for varying or controlling the resiliency of the toe pad to suit varying conditions. As shown herein a spring having appropriate resiliency to produce the desired effect is located in the recess in the pad. A plurality of springs of different degrees of

resiliency may be provided for alternative use, and the yielding quality of the central portion of the pad may thereby be controlled and may be made either greater or less than the end portions of the pad.

Another feature of the invention consists in the combination with a yielding pad member having a recess or cavity therein and a hold-down for applying pressure to the shoe, of a support for the pad member comprising a box in which the pad member is confined, the recess or cavity in the pad member permitting the pad member to be deformed into the recess in response to pressure of the shoe which pressure indents the surface of the member and causes it to assume a form corresponding to the lateral curvature of the toe at the tip seam and to distribute the pressure substantially throughout the extent of the tip seam without applying at any point an objectionable pressure.

These and other features of the invention will appear from the following detailed description when read in connection with the accompanying drawings and will be pointed out in the appended claims.

Figure 1 of the drawings shows portions of a commercial lasting machine including a toe rest which is constructed in accordance with this invention, the parts of the toe rest being shown as having adapted themselves to the shape of the shoe pressed down upon the toe pad;

Fig. 2 illustrates the relative positions of the parts before the pad adapts itself to the shoe;

Fig. 3 illustrates a modification in the mounting of the spring in the pad;

Fig. 4 is a perspective view of a toe pad centrally recessed but without a spring; and

Fig. 5 illustrates a modification of the invention in which the pad has a plurality of recesses proportioned in size to give the varying degrees of resiliency at different portions of the pad contemplated by this invention.

Referring to Fig. 1, the toe rest comprises a support 2 which is rigidly upheld on a toe post 4 and has a segmental seat for a toe pad carrier in the form of a box 6. A rubber toe pad 8 is seated in the pad box 6 and is held therein by a pin 9 which passes through

holes 10 in pad box 6 and also through slots 12 on the support 2. The pin, therefore, holds the pad in the box and also retains the box on the support, but the slots 12 permit 5 sliding movement of the box and pad relatively to the support 2 in an arc. A hold-down indicated at 14 is employed to clamp the toe portion of the shoe down against the toe pad. The pad has an opening 16 formed 10 therein which, as shown in Figs. 1 to 4, has the shape of the pad and is of considerable size. The effect of forming this opening is to reduce the resistance of the central portion of the pad to compression due to pressure 15 of the toe of the shoe upon it and to allow the toe to indent the pad and become more deeply embedded in it, as is indicated in Fig. 1, than would occur if the pad were not recessed. The opening also reduces the 20 resistance of the lateral portions of the pad as it provides a space into which the rubber may be displaced by pressure upon the pad. It may be desirable, under some conditions, to restore a portion of the resistance of the 25 central part of the pad. This may be done by introducing into the opening a suitable spring 20. By this means, the resiliency of the central portion of the pad may be locally controlled in accordance with the requirements 30 of the work.

Many of the advantages of my invention may be secured by forming a single opening in the pad, as indicated in Fig. 4, which is smaller than that employed when the 35 spring 20 is to be used and which serves to reduce the resistance of the central portion of the pad and avoids the objectional effects of excessive pressure at this point.

Fig. 5 illustrates a still further modification 40 in which the number of openings is increased and their size proportioned to the degree of resistance required in the different portions of the pad. As shown, the larger holes are arranged near the center 45 and the holes diminish in size toward the lateral portions of the pad. It is to be understood, of course, that air spaces or cavities of any kind formed in the rubber will, if properly located and of proper 50 size, have a similar effect and come within the scope of this invention.

In Fig. 3 is shown a spring which engages at one end a button 22 having a stud 24 to enter the spring and a headed 55 projection 26 which may be vulcanized into the body of the pad, or otherwise permanently secured therein. The opposite end of the spring may extend through a hole in the lower portion of the pad and rest 60 against the box 6. By this construction metallic bearing surfaces are provided for each end of the spring 20 whereby greater durability is secured. The retaining pin 9 may be positioned at one side of the 65 center out of line with the spring 20.

Having fully described my invention, I claim as new and desire to secure by Letters Patent of the United States:

1. In a lasting machine, means to hold a shoe in position in opposition to instrumentalities tending to displace the tip seam comprising, in combination, a toe rest having a resilient member with a portion thereof removed below that part of its surface on which the toe of the shoe rests, and constructed and arranged to cause the rest to yield so as to engage the shoe over an extended area running transversely of right and left lasts of different shapes, and a hold-down for clamping the shoe against 75 said rest.

2. In a lasting machine, a rest upon which to clamp the toe of the shoe at the tip seam to hold the seam from displacement, said rest comprising a block of resilient material 85 having an approximately flat toe engaging face and provided under said face with a recess extending through the block from front to back, and suitably located to enable the toe to be sunk into said face so 90 that the toe will engage an extended area thereof.

3. In a lasting machine, means to hold the tip seam of a shoe against displacement during the lasting operation, comprising a 95 toe rest and a hold-down between which the toe is clamped at or adjacent to the tip seam, said toe rest comprising a rubber pad and a box in which the lower portion of said pad is confined, the pad being provided with a recess to permit deformation of the pad into said recess when hold-down pressure is applied to the shoe on the pad and to allow a more extended area of the 100 pad in the direction of the tip seam to 105 contact with the shoe.

4. A toe pad for lasting machines comprising a block of yielding material having a cavity formed in the center portion thereof to increase the yielding capacity of that 110 portion, and interchangeable means located in said cavity for controlling the yielding quality of the central portion of the pad.

5. A toe pad for lasting machines comprising a segmental block of rubber, a 115 cavity formed in the central portion of the pad and extending laterally of the shoe toward the ends of the pad, and means for restoring to the shoe engaging face of the pad at its central portion a portion of the 120 resistance to compression removed by the formation of the cavity.

6. In a lasting machine, a toe rest for the last comprising a support and a pad consisting of a block of yielding material 125 provided with a recess under that portion of its top face which is to be engaged by the thickest part of the last, and a spring arranged in said recess to be compressed by the pressure of the last. 130

7. In a lasting machine, a toe rest for the last comprising a support and a pad consisting of a block of yielding material provided with a recess under that portion 5 of its top face which is to be engaged by the thickest part of the last, a helical spring arranged in said recess, and a cap plate for the spring in the upper wall of the re-

cess, said pad also having a socket for the spring extending through the lower wall 10 of the recess to permit the spring to rest on the pad support.

In testimony whereof I have signed my name to this specification.

JOHN J. DOLAN.
